Patented Feb. 23, 1960

187,270

MALE ELECTRICAL CONNECTOR

Matthew J. McCabe, Bristol, Conn., assignor to The Superior Electric Company, Bristol, Conn., a corporation of Connecticut

Application July 14, 1959, Serial No. 56,771

Term of patent 14 years

(Cl. D26—1)

Fig. 1

Fig. 2

Fig. 3

Fig. 4

Figure 1 is a front elevational view of a male electrical connector, showing my new design, the rear being substantially a mirror image thereof;

Fig. 2 is a side elevational view, the opposite side being substantially a mirror image thereof;

Fig. 3 is a top plan view; and

Fig. 4 is a bottom plan view thereof.

The dominant features of my new design are shown in solid lines in the drawing.

I claim:

The ornamental design for a male electrical connector, as shown and described.
